UNITED STATES PATENT OFFICE

93,378

DESIGN FOR A SPOOL HOLDER

Horace O. Barone, Buffalo, N. Y.

Application June 23, 1934, Serial No. 52,308

Term of patent 7 years

To all whom it may concern:

Be it known that I, HORACE O. BARONE, a citizen of the United States, residing at Buffalo, in the county of Erie and State of New York, have invented a new, original, and ornamental Design for a Spool Holder, of which the following is a specification, reference being had to the accompanying drawing, forming part thereof.

The figure is a perspective view of a spool holder, showing my new design.

I claim:

The ornamental design for a spool holder, as shown.

HORACE O. BARONE.
